UNITED STATES PATENT OFFICE.

MANUEL FELDMAN, OF NEW YORK, N. Y.

RUG.

1,342,259.

Specification of Letters Patent. Patented June 1, 1920.

Application filed December 27, 1919. Serial No. 347,715.

To all whom it may concern:

Be it known that I, MANUEL FELDMAN, a citizen of the United States, residing at New York, in the county of New York and State 5 of New York, have invented certain new and useful Improvements in Rugs, of which the following is a specification.

This invention relates to a rug, and more particularly to the class of combined grass 0 or straw and fabric rugs.

The primary object of the invention is the provision of a rug of this character, wherein the body thereof has its major portion formed from grass or straw and interwoven 5 with the same in a particular manner are rags, yarns or other fabric filler, so that the said rug is reinforced throughout its entirety with the fabric, the latter being located at the border and within the same in 0 directions longitudinally and transversely of the body of the rug so as to give it great strength and durability and at the same time add materially to the appearance of the rug, the design effect of the latter being identical 5 on both sides thereof so that the same is reversible, whereby it can be used with equal satisfaction on either side.

Another object of the invention is the provision of a rug of this character, wherein 0 the warp gives the entire surfaces of both sides of the rug a very rich carpety appearance and the interweaving of fabric with the straws materially strengthens said rug to assure longevity thereto and at the same time 5 avoiding any material increase in the expense of weaving or making the rug.

A further object of the invention is the provision of a rug of this character, wherein the interweaving of fabric with the straw 0 or grass enables the production of unique and ornamental design possessing permanency and consistent with the life of the rug and affording maximum strength, as the grass and straw fibers will be maintained 5 fixed without any possibility of the weakening thereof in the continued use of the rug.

A further object of the invention is the provision of a rug of this character, which is designed to afford a much more ornamental 0 and durable appearance than has heretofore been secured and thereby better adapt the rug in substitute for carpet and for interior use.

A still further object of the invention is 5 the provision of a rug of the grass type, which possesses strength and durability,

richness in appearance and inexpensive to manufacture.

With these and other objects in view, the invention consists in the features of construction, combination and arrangement as will be hereinafter fully described, illustrated in the accompanying drawing and pointed out in the claim hereunto appended.

In the accompanying drawing:

Figure 1 is a plan view of a rug of the grass type, showing its body and design thereof woven in accordance with the present invention.

Fig. 2 is an enlarged detail fragmentary 70 plan view, showing the warp and woof including the grass or straw and the fabric in associated relation to each other.

Fig. 3 is a sectional view on the line 3—3 of Fig. 2.

Similar reference characters indicate corresponding parts throughout the several views in the drawing.

Referring to the drawing in detail the rug in the construction of its body is composed of woof strands 5 of grass or straw of the kind universally employed in the weaving of grass rugs. These strands 5 of grass or straw are relatively thick or bulky, and are composed of the so-called wire 80 grass, so that the same gives bulk to the body of the rug when finished in the manufacture thereof.

Interwoven or laced back and forth or diagonal longitudinally of the body of the rug are the warp threads 6, these strands being of cotton yarn or the like and in the interweaving are passed back and forth through the grass woof strands 5 in the usual manner.

At selected intervals between the woof strands 5 to be disposed transversely of the body of the rug are rag strips 7 made from cotton or other fabrics, the strips being formed into cord or rope like lengths and have the warp strands 6 interwoven or laced therewith identical to the interweaving or lacing of said strands with the woof strands 5, the rag strips 7 being composed of colored and uncolored fabrics of wool or cotton or both so that a certain predetermined ornamental or artistic design will be present in these strips, the coloring if present being blended or consistent with the applied design to the woof and warp strands 100 which designs are usually stamped thereon.

In addition to the strips 7 and disposed

- longitudinally of the body of the rug at selected intervals are closely arranged warped strands 8 which stripe the body of the rug and in their arrangement give in conjunction with the strips 7 block design effect to the rug, the design formation by the said strips 7 and 8 being duplicated so that the opposite surfaces or faces of the rug are identical with each other so that said rug 10 can be used with equal satisfaction on either side. The strands 8 may be colored or without color and the colored strands are congruous with the ornamentality of the body of the rug. It is to be understood of course 15 that various designs or coloring effect can be had by fixing the coloring of the strips 7 and 8 and by the interposition of these strips the body of the rug is uniformly reinforced through the extent thereof.
- 20 The marginal edge of the body of the rug has stitched or otherwise secured thereto an edging tape 9 to prevent the raveling or the tearing of the body of said rug at its edges.
- 25 Adjacent to the marginal edges of the body of the rug the strips 7 and the strands 8 are arranged close to each other for a determined area to present a border design or configuration 10 to the body of the rug 30 on both sides thereof and this border further strands the rug adjacent to the marginal edges thereof.

Rugs woven as hereinbefore described

assure maximum strength to the body of the rug through the design extent thereof and effect greater ornamentality or a more elegant appearance than plain grass rugs or rugs decorated with print or stencil designs. However the rug can be stenciled or otherwise marked with applied designs in addition to the permanent or fixed designs produced by the fillers in the form of stripes, by the strands 8 arranged as hereinbefore set forth.

From the foregoing it is thought that the construction and manner of making of the rug will be clearly understood and therefore a more extended explanation has been omitted.

What is claimed is:

A patterned rug having grass woof and thread warp strands, and spaced longitudinally and transversely disposed reinforcing members interwoven with said woof and warp strands to reinforce and strengthen the entire body of the rug from edge to edge, both longitudinally and transversely of the same, certain of said reinforcing members being made from fabric filling strips, while the other reinforcing members are made from material identical with the warp strands.

In testimony whereof I affix my signature hereto.

MANUEL FELDMAN
